UNITED STATES PATENT OFFICE.

WILLIAM WILLIAMS, OF MORRISBURG, CANADA.

INSECTICIDE.

No. 825,787.

Specification of Letters Patent.

Patented July 10, 1906.

Application filed October 30, 1905. Serial No. 285,180.

To all whom it may concern:

Be it known that I, WILLIAM WILLIAMS, a subject of the King of Great Britain, residing at Morrisburg, county of Dundas, in the Province of Ontario, Canada, have invented certain new and useful Improvements in Insecticides; and I do hereby declare that the following is a full, clear, and exact description of the invention, such as will enable others skilled in the art to which it appertains to make and use the same.

My invention relates to compounds, adapted for use in destroying noxious insects, commonly called "insect-destroyers;" and my invention consists of the combination herein described.

In preparing the compound of my invention, I place eight gallons of crude creosote in the receptacle and add one gallon of oil of tar, one gallon of benzin, one gallon of paraffin-oil, and one quart of oil of cedar. These ingredients are then thoroughly mixed by stirring. The benzin dissolves the heavier in-

gredients, and the oil of tar and paraffin-oil prevent the rapid evaporation of the other ingredients. The compound thus produced is liquid in its nature and may be applied as a spray. It should be evident that these ingredients may be mixed in varying proportions, or that chemical equivalents for any of the ingredients specifically mentioned may be substituted without departing from the spirit of my invention.

Having fully described my invention, what I claim as new, and desire to secure by Letters Patent, is—

An insecticide compound consisting of eight gallons of crude creosote, one gallon of oil of tar, one gallon of benzin, one gallon of paraffin-oil, and one quart of oil of cedar.

In witness whereof I have hereunto set my hand in the presence of two witnesses.

WILLIAM WILLIAMS.

Witnesses:

DALTON ROY CRYSLER,
A. HUNTER.
